UNITED STATES PATENT OFFICE.

CHARLES B. BRATT, OF PITTSBURGH, PENNSYLVANIA.

DENTAL BRIDGEWORK

1,235,004.

Specification of Letters Patent. Patented July 31, 1917.

Application filed September 7, 1916. Serial No. 118,828.

To all whom it may concern:

Be it known that I, CHARLES B. BRATT, a citizen of the United States, residing at Pittsburgh, in the county of Allegheny and 5 State of Pennsylvania, have invented certain new and useful Improvements in Dental Bridgework, of which the following is a specification.

The invention relates to dental bridge-work and particularly to the means for securing a connection between porcelain teeth and the metal backing plates employed therewith. The invention has for its primary objects; the provision of a construction 10 (1) wherein the cutting of the porcelain is distributed in such manner as to reduce the danger of splitting or cracking, (2) wherein the central portions of the tooth is left of maximum strength, and (3) 15 which can be cheaply and accurately made. Certain embodiments of the invention are illustrated in the accompanying drawings, wherein—

Figures 1, 2 and 4 are a side elevation, 20 rear face view, and end elevation respectively, of a tooth constructed in accordance with my invention; Fig. 3 is an enlarged section on the line III—III of Fig. 2; Figs. 5 and 6 are a face view and end elevation respectively, of a backing for use in connection with the tooth shown in Figs. 1, 2 and 4; Figs. 7 and 8 are rear face and end elevation views respectively, of a modification; Figs. 9 and 10 are a face view and end elevation respectively, of a backing for use in connection with the tooth of Figs. 7 and 8; Figs. 11 and 12 are rear face and end elevation views respectively, of another modification; Figs. 13 and 14 are a face view and 30 end elevation respectively, of a backing for use in connection with the tooth of Figs. 11 and 12; and Fig. 15 is a transverse section through still another modification.

Referring first to the construction of 35 Figs. 1, 2, 3 and 4, 1 is a porcelain tooth which may be of any desired configuration and which is provided on its rear side with a pair of longitudinally extending grooves, each comprising the portion 2, circular in 40 cross-section, and the slot 3, which slot 3, as indicated in Fig. 2, is of less length than the larger circular portion of the groove beneath. A backing plate 4 (Figs. 5 and 6) is used in connection with this tooth, such 45 backing comprising a metallic plate prefer-

ably provided with the two integral ribs. These ribs each consist of a circular portion 5 and a neck portion 6, and it will be understood that the circular portion 5 fits into the portion of the groove 2 of circular cross-section and that the neck 6 lies in the slot 3. The neck 6 terminates short of the end of the circular portion 5, as indicated in dotted lines in Fig. 5, so that when the backing is applied to the tooth the end of the circular portion 5 extends to the inner end of the circular portion 3 of the groove in the tooth, so that a very secure support at the inner end of the rib is secured.

This form of construction is advantageous 50 since the tooth is not weakened along the center line A by the cutting of the grooves, and it is at the center line that breakage ordinarily occurs with teeth of this character. The grooves are each located intermediate 55 the center line of the tooth and its outer edge, and can be made much smaller in cross-section than where only a single groove is used as has heretofore been the practice in most cases. The making of the bottom 60 portions 2 of the grooves circular also eliminates the danger of breaking or cracking, such as is present where grooves having sharp corners are employed. It will also be seen that relatively small grooves of this 65 character can be spaced a relatively great distance from the center line of the tooth, thus giving a better resistance against twisting strain than is the case where the grooves are necessarily placed relatively close to the 70 center line of the tooth. Another advantage in this construction consists in the ease with which the grooves can be cored out and subsequently reamed to the exact size desired, it being much easier to cut a groove 75 substantially circular in cross-section than one having an angular cross-section. Other advantages incident to my construction will be readily apparent to those skilled in the 80 art.

In the construction of Figs. 7 and 8 the 85 grooves 7 are the same as in the first construction except that the circular portions of these grooves are tapered, as indicated in dotted lines in Fig. 7. The backing 8 employed with this construction is provided with ribs having tapered circular portions 9 and necks 10 connecting them with the plate, the shape of the ribs corresponding to 90 that of the grooves. The tapered form of 95 110

the ribs gives the most advantageous distribution of metal with respect to the strain imposed thereon.

Figs. 11 and 12 illustrate still another modification wherein the circular portions 11 of the grooves have their center lines inclined with respect to the center line of the tooth, as indicated in the dotted lines, Fig. 11, the angle of inclination approximating that of the sides of the tooth. The slot portions 12 of the grooves are parallel to each other as are also the outer side walls 13 of the circular portions 11. The backing 14 used with this tooth is provided with tapered ribs 15 having their center lines inclined to correspond with those of the grooves. The neck portions 16 of the ribs are parallel. The edges of the slots 12 and necks 16 are rounded or provided with fillets as indicated in Figs. 12 and 14, thus differing slightly from the previous constructions in which the corners of these portions are left relatively sharp. The inclining of the grooves and pins gives a still better support for the tooth than that secured in the preceding constructions, the arrangement being preferable in this respect to that

of the other constructions, although somewhat more difficult to make.

Fig. 15 illustrates the cross-section of still another modification wherein the tooth 17 is provided with grooves 18, the circular portion of such grooves being off center with respect to the slot portions.

What I claim is:

A tooth construction comprising a porcelain tooth provided on its rear side with a pair of grooves, each extending longitudinally of the tooth from its butt and lying intermediate the center line of the tooth and its edge and having their inner sides and their center lines inclined away from the center line of the tooth but with their outer side edges parallel thereto, and having their upper portions relatively narrow with their lower portions larger in cross-section and substantially circular tapering to a less diameter from the butt end inward, and a backing provided with a pair of ribs for engaging the said grooves, the said ribs having their center lines and inner sides inclined away from each other but with their outer sides parallel.

CHARLES B. BRATT.
